UNITED STATES PATENT OFFICE.

WILLIAM H. HAZARD, OF JANESEVILLE, WISCONSIN, ASSIGNOR TO GENERAL MOTORS CORPORATION, OF DETROIT, MICHIGAN, A CORPORATION OF DELAWARE.

HEATING FURNACE.

Application filed August 22, 1921. Serial No. 494,269.

To all whom it may concern:

Be it known that I, WILLIAM H. HAZARD, a citizen of the United States of America, and a resident of the city of Janesville, 5 county of Rock, and State of Wisconsin, have invented certain new and useful Improvements in Heating Furnaces, of which the following is a full, clear, concise, and exact description, such as will enable others 10 skilled in the art to which the invention relates to make and use the same, reference being made therein to the accompanying drawings, which form a part of this specification.

15 My invention relates to high temperature furnaces, and particularly to such as are used to heat articles that are to be forged and to which a part has to be welded, such as plowshares which commonly have a 20 separate point welded to the main body of the share.

The principal object of my invention is to provide an improved furnace consisting of 25 two heating chambers, one in which the article is heated all over to a temperature suitable for forging, and in the other of which the heat is concentrated on a small portion to which another piece of metal is to be welded.

30 A further object of my invention is to provide an improved furnace having a means for continuously moving the articles or devices that are to be heated from an opening in one end wall of the furnace to an opening 35 in the other end wall.

A further object of my invention is to provide an improved furnace wherein the heating chambers are so arranged that the article that is to be heated, upon entering the 40 furnace, encounters only a moderate temperature and is gradually moved along by a conveying means into a region of higher temperature; so that when it reaches the end of the furnace it has reached its maximum 45 temperature. This prevents the metal of the article heated from being crystallized or otherwise injured, as it would be if it were heated too quickly.

A further object of my invention is to 50 provide an improved furnace consisting of two chambers, one of which has a consid-

erably higher temperature than the other; and wherein the surplus heat of the hotter chamber is used to partially bring the temperature of the other up to a given degree. 55

A further object of my invention is to provide an improved furnace consisting of two chambers, one of which is heated to a higher temperature than the other; and wherein the two chambers are constructed 60 in such a way that the one which generates the higher temperature may be removed and another built in its place without disturbing the chamber which generates the lower temperature; as it is obvious that the chamber 65 having the higher temperature will burn out much sooner than the other.

With the above and other objects in view, my invention consists of an improved high temperature furnace and subsidiary parts 70 and auxiliary features thereof illustrated in the accompanying drawings and hereinafter described and claimed; and in such variations and modifications thereof, within the scope of the concluding claims, as will be 75 obvious to those skilled in the art to which my invention relates.

Referring now to the drawings wherein the preferred embodiment of my invention is illustrated:—

80 Figure 1 is a sectional plan view of my improved furnace, taken upon the line 1—1 of Figure 2.

Figure 2 is a sectional side view and is taken upon the line 2—2 of Figure 1.

Figure 3 is a sectional view taken upon the line 3—3 of Figure 1.

Figure 4 is an end elevation as seen from a position to the right of Figure 1.

Figure 5 is a sectional view taken upon the line 5—5 of Figure 1.

In the drawings, the reference numeral 10 designates a heating chamber 18 in which articles to be heated such as plowshares 11 are brought to a forging heat, while 12 is 95 another heating chamber in which the points 13 of the shares 11 are brought to a welding heat. The chamber 10 is formed by fire brick walls 14, a roof 15 and floor 16; while the chamber 12 is formed by walls 17, a roof 18 and floor 19. Through the wall 14 and into the chamber 10 runs a gas burner 20

from which comes the flame which supplies the forging heat; and through the walls 17 and into the chamber 12 runs a gas burner 32 from which comes the flame which supplies the welding heat.

- Through the chamber 10 runs a conveyor comprising two conveyor chains which are made up of links 21 held in proper relation to each other by braces 22. On each link 21 is a lug 23 upon which the plowshares 11 rest. The conveyor chains are driven by the two sprockets 24 through the shaft 25 and run around the two idler sprockets 26, mounted on the shaft 27. In the furnace the links 21 run upon pipes 28, through which cold water is pumped, which keeps the pipes 28 from being burnt out by the extreme heat and keeps the conveyor chain from becoming too hot.
- 10 In the walls 14 and 17 are openings 29 in the form of long narrow slots alongside which the conveyor runs and through which the points 13 of the shares 11 pass. The shares are placed upon the conveyor chain 25 at the left-hand end of the furnace and pass thereinto through an opening 30, and are moved very slowly toward the right. When they first enter the chamber 10 the heat is not very intense, but as they move to the right the temperature increases. By the time they approach the chamber 12 the whole share has been brought to a forging heat. Therefore when the point 13 enters the chamber 12 it is not subjected to a severe change in temperature, as it is already very hot and the difference between the forging and welding heats is not enough to affect the composition of the metal.

- At the right-hand end of the furnace is an opening 31 through which the operator of a drop hammer removes the red-hot shares. He then performs the forging and welding operations and returns to the furnace for another plowshare. In case the operator should fail to remove one of the shares through the opening 31, it will pass through the opening 33 in the right-hand walls 14 and 17 of the heating chamber 10, 12 and cause a balanced fireproof trap door 34 to swing outwardly, and run off the end of the conveyor chain and drop to the floor. The door 34 serves to retain the heat within the chambers 10 and 12; and the lugs 23 on the links 21 of the conveyor chains are provided to keep the shares up off the chains, so that the heat will be allowed to circulate under the shares as much as possible.

- The roof 15 of the chamber 10 curves downward toward the conveyor chain side of the furnace, and the flame shoots from the burner 20 diagonally across the chamber and is deflected downwardly by the roof and around the shares 11, heating them gradually to a forging heat. In the chamber 12 the flame shoots from the burner 32

directly on the under side of the points 13 of the shares 11, heating them to a white-hot heat for welding.

It will be seen that as there is considerable pressure within the chamber 12, quite an amount of the heat therein will be forced out through the openings 29 into the chamber 10, thus helping to heat this last-mentioned chamber.

Operated by the heat within the chamber 12 is a thermostatic regulator 35 which controls the burner 32, thus keeping the temperature in the chamber at the proper degree for welding; as it is very necessary that the welding temperature should stay the same, while the forging temperature in the chamber 10 may vary considerably without affecting the operation of the furnace as a whole. The chambers 10 and 12 are shown quite short in order that the views illustrating the invention will not be inordinate long. They may as a matter of course be made of any length, and ordinarily their length will be such that more than three plow shares at a time will be in the chamber 10, and more than two at a time will be having their points heated in the chamber 12, in order that both the forging and the welding heats will be imparted to the shares gradually as they move through the furnace.

Having thus described and explained my invention I claim and desire to secure by Letters Patent:

1. In a furnace of the class described, a heating chamber and means for heating the same; a second heating chamber partitioned off from but which second chamber is in permanently open communication with said first-mentioned chamber through a restricted opening; means for heating said second chamber to a temperature higher than that of said first mentioned chamber; and means for moving articles to be heated through the furnace.

100 105 110 115 120

2. In a furnace of the class described, a heating chamber and means for heating the same; a second heating chamber in permanently open communication with said first-mentioned chamber through a slot extending along the same; means for heating said second chamber; and a conveyor adapted to move articles to be heated through the furnace and which conveyor extends alongside the slot aforesaid.

125 130

3. In a furnace of the class described, a heating chamber and means for heating the same; a second heating chamber in permanently open communication with said first mentioned chamber through a slot extending throughout the length of said second chamber; means for heating said second chamber to a temperature higher than that of said first-mentioned chamber; and a conveyor extending through openings provided in the wall of the furnace and through said

first-mentioned chamber and alongside the slot aforesaid, and adapted to move articles to be heated through the furnace.

4. In a furnace of the class described, a heating chamber and means for heating the same; a second heating chamber in permanently open communication with said first-mentioned chamber through a slot extending alongside the same; means for heating said 10 second chamber to a temperature higher than that of said first-mentioned chamber; a conveyor for articles to be heated extending through the furnace and alongside the slot aforesaid; and an opening provided in 15 the wall of the furnace and located opposite said slot.
5. In a furnace of the class described, a heating chamber and means for heating the same; a second heating chamber structurally independent of said first-mentioned chamber and in permanently open communication therewith through an opening; means for heating said second chamber; and a conveyor for articles to be heated extending through said first-mentioned chamber 20 and adjacent the opening aforesaid.
6. In a furnace of the class described, a heating chamber and means for heating the same; a second heating chamber in perma- 25

nently open communication with said first- 30 mentioned chamber; means for heating said second chamber to a temperature higher than that of said first-mentioned chamber; and means for moving articles to be heated through said first-mentioned chamber, and 35 portions only of the articles through the permanently open communication aforesaid and into said second-mentioned chamber.

7. In a furnace of the class described, a heating chamber and means for heating the same; a second heating chamber in permanently open communication with said first-mentioned chamber; means for heating said second chamber to a temperature higher than that of said first-mentioned chamber; 40 means for moving articles to be heated through said first-mentioned chamber, and portions only of the articles through the permanently open communication aforesaid and into said second-mentioned chamber; 45 and an opening provided in the wall of the furnace adjacent said second-mentioned heating chamber and through which the heated articles may be removed from the furnace. 50

In testimony whereof I affix my signature.

WILLIAM H. HAZARD.
